DEDENTING MACHINE FOR CLOSED END CONTAINERS

Edward C. Kradoska, Melrose Park, Pa.

Application November 22, 1949, Serial No. 128,811

9 Claims. (Cl. 153—32)

1

My invention relates to a de-denting machine of the type used for removing dents, bumps and other deformations from the body or from the body bulges of metal drums.

One object of the invention is to produce an improved machine of this type.

When a metal drum is open at either end thereof, the dents and bumps referred to are removed by means of apparatus which includes an inner roll which is inserted through the open end of the drum so as to engage the inner side of the portion of the drum to be rolled, and an outer roll which registers with the inner roll and engages the outer side of the portion of the drum to be rolled. Such apparatus, however, can not be used on drums that have both of their ends closed.

It is therefore a further object of the invention to produce an improved body roller which can be effectively used for removing dents and bumps from the body and from the body bulges of a drum which is closed at both of its ends.

A still further object is to produce an improved rolling machine which automatically adjusts itself to drums the body bulges of which are at varying distances from the ends or from the center of the drum.

A still further object is to produce an improved machine of the type set forth which is substantially automatic or which lends itself to substantially automatic operation.

These and other objects are attained by my invention as set forth in the following specification and as shown in the accompanying drawings in which:

Fig. 1 is a view, partly in vertical section and partly in front elevation, of a rolling machine embodying my invention, certain parts being omitted and the machine being shown in non-operating position.

Fig. 2 is similar to Fig. 1 but shows the machine in operating position.

Fig. 3 is a diagrammatic top plan view illustrating the structure and operation of certain of the parts which could not be adequately shown in Figs. 1 and 2.

Fig. 4 is an enlarged, fragmentary, vertical sectional view showing details of construction.

Fig. 5 is a greatly enlarged, fragmentary view showing the manner of operation.

Fig. 6 is an enlarged view looking in the direction of line 6—6 on Fig. 3.

The rolling machine illustrated includes a housing formed of a bottom wall 10, a back wall 11, end walls 12, and a top wall 13. The front

2

of the machine is left open but is adapted to be closed by doors 14 in a manner and for a purpose hereinafter set forth. The back wall 11 and the doors 14 are curved, as best shown in Figure 3, so as compactly to accommodate a drum 15 formed with a body 16 and with upper and lower body bulges 18 and 19.

The housing is suitably supported on a base or pedestal 20, only a part of which is shown in Fig. 1. Keyed to the pedestal 20, as at 21, is a threaded stem 22, which extends through a threaded sleeve 23 rotatably mounted on the pedestal 20. The sleeve 23 is rotated by means of a motor 24 which drives a bevel gear 25 which meshes with a gear 26 carried by the sleeve 23. The motor 24 is energized or de-energized by means of a conventional switch not shown. By this arrangement, when the sleeve 23 is turned in one direction the threaded stem 22 will move upwardly and vice versa.

The upper portion of the stem 22 is provided with a shoulder 29, which shoulder supports a hub 30 in a manner to be vertically movable with the stem. The hub 30 rotatably supports a platform 32 which is adapted to support a drum 15, as shown in Fig. 1. Suitable anti-friction bearings 33 are interposed between the platform 32 and the hub 30. By this construction, the platform 32 is freely rotatable relative to the hub 30 and the upper end 31 of the stem 22 regardless of the position of the hub and regardless of whether the hub is in vertical motion or not.

Above the drum 15 I provide a plate 36 which is secured to the lower end of a hollow shaft 40 which passes through a fixed thrust-bearing 41. The shaft 40 and the plate 36 are movable vertically relative to the bearing 41 and are normally biased downwardly by means of springs 42 placed between the thrust bearing 41 and the plate 36 as best shown in Fig. 1. The shaft 40 is rotated by means of a driven pinion 44 which engages a gear 45 carried by the shaft, it being noted the length of the pinion is greater than the thickness of the gear 45 so that engagement is maintained between the gear 45 and the pinion 44 as the plate 36 and the shaft 40 are moved between their upper and lower portions. See Figs. 1 and 2. The worm 44 is driven by any suitable electric motor, not shown, and it is intended that the shaft 40 and the plate 36 shall be rotated continuously as long as the machine is in use.

The plate 36 is provided with a pendent driving and sealing ring-gasket 48 which, when the drum is raised, is adapted to engage the upper

end wall 49 of the drum, so as to rotate the drum upon rotation of the plate 35 and the shaft 40. The ring gasket 48 also coats with the plate 36 and the end wall 49 of the drum to form a chamber 50 which communicates with the interior of the drum through the usual bung hole 52. A flexible pipe 54, leading from a source of compressed air, not shown, delivers air through hollow shaft 40 into the chamber 50. See Figs. 1 and 4.

The machine illustrated further includes a pair of upper rollers 55 and a pair of lower rollers 56, for rolling corresponding portions of the body 16 of the drum. The upper rollers 55 are provided with circular grooves 57 for rolling the upper body bulges 18 and the lower rollers 56 are provided with similar grooves 58 for rolling the lower body bulges 19 of the drum. See Figs. 1 and 5.

The rollers 55 and 56 are freely rotatable on uprights 60 and are actuated into or out of engagement with the drum by means of suitable linkage 61 and a double acting air cylinder 62. The air cylinder 62 and the linkage 61 connecting it to the uprights 60 are conventional and, hence, are not shown nor described in detail. It is sufficient to state that, when compressed air is admitted into the cylinder 62, in one manner, the rolls 55 and 56 are moved to the broken line position of Fig. 3 in which they engage the drum, and vice versa.

In most cases, the body bulges 18 and 19 on the drums are so located that, when the drum is raised into engagement with the ring gasket 48, the body bulges will register with the circular grooves 57 and 58. But, in order to adapt the machine for use on drums the body bulges of which are located at various distances from the end walls of the drum, I provide means whereby the rolls 55 and 56 will automatically "hunt" and move up or down so as to bring the circular grooves 57 and 58 into registration with body bulges. To this end the rolls 55 and 56 are supported by springs 64 and are provided with spiral grooves 65 and 66, respectively, which spiral grooves extend above and below, and communicate with, the circular grooves 57 and 58, respectively, as best shown in Figs. 1 and 5. It will be understood that the rolls 55 and 56 are freely slideable vertically on the uprights so that, if the upper body bulge 18, for example, should be below the circular groove 57, it will engage the portion of the spiral groove 65 which is below the circular groove 57 in the rolls 55, as shown in the upper portion of Fig. 5, and vice versa. Likewise, if the body bulge 19 happens to be higher than the circular groove 58 of the rolls 56, it will engage the portion of the spiral groove 66 which is above the circular groove 58, and vice versa. In any event, the engagement of the body bulges of the rotating drum with the spiral grooves 65 or 66, of the freely rotating and freely, vertically, slideable rolls 55 and 56, will result in raising or in lowering these rolls, as the case may be, until the circular grooves 57 and 58 of these rolls register with and are engaged by the respective body bulges 18 and 19.

In order accurately to center the drum, I provide three inverted conical rolls 70 which are freely rotatable about stub shafts 72 the axes of which are equidistant from the axis of the shaft 40 and from the axis of the stem 22. The downward movement of the rolls 70 is limited by pins or stops 74 and their upward movement is opposed by springs 75 confined between the conical members and a shoulder 76 formed on the stub shafts 72. As will be best seen from Fig. 4, the

rolls 70 are so positioned that, as the drum is move upwardly, its upper edge rides on the upwardly flaring surfaces of these rolls and the drum is thus centered. It will be noted that the rolls 70 are engaged by the upper edge of the drum after the drum has been engaged with, and set in motion by, the ring gasket 48. The rotation of the drum while its upper edge is moving upwardly on the surfaces of the rolls 70 facilitates the centering of the drum.

In order to limit the downward movement of the drum and thus avoid breakage which may result if the motor 24 continued to operate after the parts have reached a predetermined low position, I provide a normally closed switch 80 which is connected to the motor 24 by wires 81. This switch is located at the desired point below the platform 32 so that when the platform 32 has reached a predetermined low position, such as that shown in Fig. 1, the platform 32 will engage and open the switch 80 to de-energize the motor 24. Likewise, for limiting the upward movement of the drum I provide a normally closed switch 82 which is also connected to the motor 24 by wires 83. This switch is located above the platform 36 so that, when the drum moves this platform upwardly, against the action of springs 42, the switch 82 will be engaged and opened by the platform 36 to de-energize the motor 24. The switch 82 is so located relative to the upper side of the plate 36 that it is opened only after the ring gasket 48 and the springs 42 have been somewhat compressed thus assuring adequate engagement between the upper end of the drum and the ring gasket before the upward movement of the drum is arrested.

The doors 14 are carried by uprights 85 which are hinged, as at 86, to front extensions 87 of the side walls 12 of the housing, as best shown in Figs. 2 and 3. The doors 14 are moved to the closed position which is shown in solid lines in Fig. 2 and in broken lines in Fig. 3, or to the open position shown in solid lines in Fig. 3, by means of an air cylinder 88 which moves a rack 89 to rotate a gear 90 on one end of a shaft 91 which also carries gears 92 which mesh with gears 93 on the uprights 85. The air cylinder 88 and its manner of operation are conventional and hence are not shown nor described in detail. It is sufficient to say that when compressed air is admitted into the cylinder 88, in one way, the doors are moved to closing position and vice versa.

The operation is as follows:

The shaft 40 set in motion to rotate the plate 36, the drum to be rolled is placed on platform 32 and motor 24 is energized to raise the drum into engagement with the driving and sealing ring gasket 48, the drum being centered by contact with roll 70, if such centering be necessary. During upward movement of the drum, compressed air is admitted into cylinder 88 to close the doors 14 and, substantially simultaneously, compressed air is admitted into the interior of the drum through pipe 54, shaft 40 and bung hole 52. As the air pressure within the drum reaches a predetermined degree, compressed air is admitted into air cylinder 62 to move rolls 55 and 56 into engagement with the drum with the desired degree of pressure. When the rolls 55 and 56 engage the drum, the circular grooves 57 and 58 will register, in most cases, with the body bulges 18 and 19 to be rolled, and in other cases, the upper or lower portions of the spiral grooves 65 and 66 will engage the body bulges and will

move the rolls 55 and 56 up, or down, as may be necessary, to bring the circular grooves into alignment with the body bulges.

After the drum has been rolled the prescribed number of times, the air cylinder 62 is activated to move the rolls 55 and 56 out of engagement with the drum; the air is exhausted from the drum; the motor 24 is activated to lower the drum, and as the drum moves to its lower position, the air cylinder 88 is activated to open the doors 14.

The operations listed, in direct or in inverse order, can be carried out manually but if it is desired to make the operation automatic, suitable timing and relay devices of any well known design can be used. For example, when hydraulic or pneumatic means are used, pressure sensitive devices can be employed for carrying out the operations in their proper sequence. When mechanical or electro-mechanical means are employed, suitable relays, timers, cams, etc. can be used. Since the various control mechanisms mentioned are available, and since the manner in which they should be installed and connected is indicated, it is not necessary to show or describe the same in detail. Also, the machine may be mounted horizontally instead of vertically and automatic conveyor means can be added for delivering the drum to be rolled to the machine and for removing the rolled drum from the machine.

Since the sole purpose of the compressed air is to create the desired pressure within the drum to resist the action of the rollers 56 and 55, it is obvious that a fluid pressure other than air pressure can be used, such for example, as water or oil or any other liquid pressure.

What I claim is:

1. A rolling machine including a first end plate, means for rotating said first end plate, a second end plate aligned with said first end plate, means for mounting said second end plate for free rotation about the axis of rotation of said first end plate, said plates being spaced apart so as to receive a drum to be rolled therebetween with the end walls of said drum in a position to be engaged by said plates respectively, driving means for moving said second end plate toward said first end plate to clamp said drum between said end plates, a freely rotatable roll having a body portion for rolling a body portion of the drum and having a circular groove for rolling a body bulge on the drum, means for creating a predetermined fluid pressure within the drum, and means for bringing said roll into engagement with the drum with a predetermined pressure.

2. The structure recited in claim 1 together with means responsive to the movement of the drum to a predetermined point in the direction of said second end plate for deactivating the said driving means.

3. The structure recited in claim 1 together

with means responsive to the movement of the drum to a predetermined point in the direction of said first plate for deactivating the said driving means.

4. The structure recited in claim 1 together with yielding means urging said first plate toward said second plate.

5. The structure recited in claim 1 in which said roll is mounted for free movement longitudinally of the drum.

6. The structure recited in claim 5 in which said roll has spiral grooves formed therein which communicate with said circular groove and extend in the direction of the axis of rotation of said roll.

7. The structure recited in claim 1 in which said second plate constitutes a platform on which the drum to be rolled is placed, and in which the first plate is positioned above said second plate and is engaged by the upper end of the drum upon vertical movement of the second plate.

8. The structure recited in claim 1 together with a casing enclosing said drum and having one end thereof open, a door for closing said open end, and means for moving said door to one position in which it closes said open end of said casing and to another position in which it does not close said open end of said casing.

9. A rolling machine including a first end plate, means for rotating said first end plate, a second end plate aligned with said first end plate, means for mounting said second end plate for free rotation about the axis of rotation of said first end plate, said plates being spaced apart so as to receive a drum to be rolled therebetween with the end walls of said drum in a position to be engaged by said plates respectively, driving means for moving said second end plate toward said first end plate to clamp said drum between said end plates, a freely rotatable roll having a body portion for rolling a body portion of the drum and having a circular groove for rolling a body bulge on the drum, and means for bringing said roll into engagement with the drum with a predetermined pressure.

EDWARD C. KRADOSKA.
